UNITED STATES PATENT OFFICE.

HARVEY ISERMAN, OF NEW HYDE PARK, NEW YORK, ASSIGNOR TO MULTIPLE-GRAVE-BAR ENDLESS CHAIN STOKER COMPANY, A CORPORATION OF NEW YORK.

MECHANICAL STOKER.

1,114,142.

Specification of Letters Patent. Patented Oct. 20, 1914.

Application filed September 11, 1911. Serial No. 648,747.

To all whom it may concern:

Be it known that I, HARVEY ISERMAN, a citizen of the United States, residing at New Hyde Park, in the county of Nassau 5 and State of New York, have invented a certain new and useful Improvement in Mechanical Stokers, of which the following is a full, clear, and exact description.

My invention is an improvement in mechanical stokers of the endless traveling grate type, and relates more particularly to improvements in the construction and mounting of the "retarding plate", or bridge, located at the rear of the traveling 15 grate.

The object of my invention is to provide a retarding plate or bridge which shall be of fire resisting material and the parts of which shall be economical to construct 20 and easy and convenient to replace.

Further objects of my invention will hereinafter appear in the specification and be pointed out in the appended claims.

Figure 1 is a vertical section through the 25 rear part of a furnace and a stoker embodying my invention, taken on a plane between the traveling grate and the side frame; Fig. 2 is a front view of the retarding plate or bridge, partially broken away to show the 30 manner of attaching the fire brick to the supporting plate; and Fig. 3 is an enlarged perspective of the fire bricks employed in the construction of the retarding plate or bridge.

As shown in the drawings, 1 is a steam 35 boiler mounted in the usual furnace structure, of which I have shown only the side walls 2 and the bridge wall 3 with its bridge 4 over which the products of combustion escape to the stack. The endless traveling grate, which may be of any desired type is indicated at 5. The grate runs over rear sprockets 6 mounted on a sprocket shaft 7 journaled in the grate frame. The grate 40 frame is composed of upper horizontal members 8 and lower horizontal members 9, joined by standards 10. I have shown the frame as made of flat plate but any desired form of structural iron or steel may be employed. The upper horizontal member 8 is continued beyond the rear standard 10 a sufficient distance to form a support, through the angle 13, for the rear plate 11 which forms the front wall of the ash pit 45 and also carries the supports for the retard-

ing plate or bridge. Plates 12 riveted to the standards 10 opposite the lower members 9 also serve to support the plate 11 through the angle 13 to which 11 is riveted. Riveted to the rear side of plate 11 are angles 14, 60 (one on either side of the furnace) and the shelf 15. The side plates 16 of the ash chamber are secured to the angles 14 and to angles 17 attached to the bridge wall 3. The ash chamber thus has front wall 11, rear 65 wall 3 and side walls 16. The ash chamber has a floor 18, which swings against the shelf 15 and is hinged at 19 to supports 20 on the wall 3 in such manner as to permit dumping of ashes into the ash car 23 when 70 desired, but to normally close the opening in the bottom of the ash chamber and prevent the passage of air there through to the stack.

On endless traveling grates the fuel bed 75 decreases in thickness from front to rear due to consumption of the coal; and it is of importance that it should not become too thin at the rear for the reason that an excess of air would then pass up through it, 80 resulting in a loss of efficiency. In order to thicken the fuel bed by backing up the ash and partially consumed fuel, and also to reduce as much as possible the opening for the passage of air behind the grate to the 85 flue, I provide a retarding plate or bridge 24. This bridge comprises a metallic bottom plate 25, carrying special fire brick 26 (of which four are shown though any desired number may be employed). The plate 90 25 is provided with a plurality of straps 27 into which fit trunnion pins 28 projecting from standards 29 bolted to the plate 11. The retarding plate or bridge is thus mounted to swing about the trunnions 28 in order 95 that any obstruction, as for instance, an unusual accumulation of clinker, may be allowed to pass thereunder, so as not to damage the nose N of the brick 26. As shown, the pivot point is much to the rear of 100 the center of gravity of the retarding plate or bridge, so that it will be returned to its position, as determined by the stops 30, by its own weight. However, I prefer to add means for positively returning the retarding plate or bridge quickly to position. The preferred form of such means, shown in the 105 present instance, consists of one or more compression springs 31.

The stops 30 are so designed and located 110

that the nose N of the retarding plate approaches very closely to, but just misses contact with the traveling grate or bridge; the relative distance between these two elements being slightly exaggerated in Fig. 1 for the sake of clearness of the drawing.

The fire brick 26 which form the heat resisting face of the retarding plate or bridge are clearly shown in perspective in Fig. 3. 10 The recesses 32 (one on either side of each brick) receive bolts 33 for attaching the brick to the bottom plate 25. Slots 34, passing the entire width of the brick, receive a rib 35 on the bottom plate to which rib is 15 transmitted the horizontal thrust exerted against the brick. I have shown the rib 35 as being formed by an angle iron bolted to the bottom plate 25, but it may be formed of other suitably shaped iron, or may be 20 integral with the bottom plate if desired.

Asbestos packing 36 is placed around bolts 33 and angle 35 and between the bricks 26 and the plate 25 to provide a slightly resili- 25 ent medium therebetween and to lessen the conduction of heat to the plate 25. The brick are also grooved or fluted at 37 to provide air passages under the brick to aid in the cooling of plate 25.

The manner of operation of the device is 30 apparent. The ashes and partially consumed fuel are carried forward by the grate, the direction of travel of which is indicated by the arrow A. As the grate and retarding plate are in such close proximity, the ashes, 35 to escape from the grate, must pass over the front inclined surface of the retarding plate. They are thus backed up to considerable distance in front of said plate and an excess of air is prevented from passing through 40 the rear part of the grate and also air is prevented from passing between the grate and the retarding plate. Due to the crowding action produced by the mass of ashes on the grate, the ashes are finally forced 45 up over the retarding plate 24 and fall down into the ash chamber behind, from

which they are from time to time dumped by dropping the plate 18.

I am aware that it is old, in connection with mechanical stokers of the endless traveling grate type, to provide retarding plates or bridges of metal or water cooled metal. But, in-case that uncooled metal is employed it is soon burned out; and, when hollow wa- 50 ter cooled structures are employed, there is 55 liability of scale forming and the parts burning out. When such accidents occur leaks result which are difficult and expensive to repair and which necessitate allowing the fire to go out. In my construction there are 60 no water cooled parts to get out of order and the metal parts are not exposed to the high heat of the combustion chamber.

Having thus described my invention, what I claim is:—

65

1. In a mechanical stoker, an endless trav- 70 eling grate, a frame for supporting said grate, a rear plate carried by said frame, stops and trunnions mounted on said rear plate, a bottom plate mounted on said trun- nions and normally engaging said stops, and a covering of fire resistant material for said bottom plate.

2. In a mechanical stoker, an endless trav- 75 eling grate, a frame for supporting said grate, a rear plate carried by said frame, stops and trunnions mounted on said rear plate, a bottom plate mounted on said trun- nions and normally engaging said stops, springs mounted on said rear plate and tend- 80 ing to return the bottom plate to engage- ment with the stops, fire brick mounted on the bottom plate, means for securing the fire brick to the bottom plate and means for preventing displacement of the fire 85 brick on the bottom plate.

In testimony whereof, I hereunto affix my signature in the presence of two witnesses.

HARVEY ISERMAN.
